(57) **CLAIM**

The ornamental design for a storage enclosure, as shown and described.

DESCRIPTION

FIG. 1 is a perspective top front right view of a storage enclosure with a lid in a closed position, showing my new design;

FIG. 2 is a perspective top front right view of a storage enclosure with a lid in an open position, showing my new design thereof;

FIG. 3 is a front elevation view thereof, with the lid in a closed position;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof; and,

FIG. 9 is a cross-sectional view taken at line 9-9 in FIG. 3.
